BLADE DISPENSING CONTAINER

Edgar A. Nelson, New York, N. Y., assignor to
 American Safety Razor Corporation, Brooklyn,
 N. Y., a corporation of Virginia

Application February 14, 1948, Serial No. 8,391

4 Claims. (Cl. 206—16)

1

This invention relates to an improved blade containing magazine which dispenses the contained blades and more particularly to a magazine wherein the dispensing is effected by advancing single blades in succession part way out of the magazine to permit its projected end to be engaged and its removal completed manually for manual placement in a razor.

The blades for which the magazine are devised are of the thin flexible wafer type. The separation of a single blade from a contained stack of such blades presents these problems among others: the danger of marring a shaving edge; the tendency of the underlying blade to adhere to and advance with the one being separated; and where, as here, the blade is only partially projected, the lack of a firm hold on the projected blade and the danger of its retreat back into the container.

Among the more important objects of my invention therefore are: an improved and inexpensive blade magazine from which blades can be projected one at a time and more particularly a magazine of this type which is comprised of few parts which can be readily assembled and loaded with blades; the provision in a blade magazine, of an improved dispensing means whereby only a single blade can be separated from a stack at a time; the provision of an improved arrangement wherein a partially projected blade will be held firmly for manual completion of the blade separation, and more particularly wherein the retreat of a partially projected blade is prevented.

For the attainment of these objects and such other objects as may hereafter appear or be pointed out, I have illustrated an embodiment of my invention in the drawings wherein:

Figs. 1, 2 and 3 are perspective views each of one of the three parts of which my magazine is comprised;

Fig. 4 is a perspective view of these three parts in their assembled relation to complete the magazine;

Fig. 5 is a vertical section on an enlarged scale taken on line 5—5 of Fig. 3;

Fig. 6 is a top elevational view on an enlarged scale, of part of the front wall of the container;

Fig. 7 is a section on an enlarged scale taken on line 7—7 of Fig. 3;

Fig. 8 is a section on an enlarged scale taken on line 8—8 of Fig. 4;

Figs. 9, 10 and 11 are sections similar to that of Fig. 8, showing successive stages in advancing a blade from out of the container;

Fig. 12 is a section taken on line 12—12 of Fig. 4, also on an enlarged scale; and

2

Fig. 13 is a perspective view similar to that of Fig. 4, however with the blade partially projected from the magazine.

For convenience of illustration, the enlargement of the scale of Figs. 5 to 12, inclusive, are not of the identical order.

Upon reference to Sheet 2 of the drawings, it will be observed that the blades B contained within the magazine in the illustrated embodiment are shown as of a standard flexible wafer type slotted longitudinally to receive the blade locating bar of one type razor and which slot is widened transversely of its length to provide openings B² and B³ to receive blade locating pins of Patent No. 875,274.

The embodiment illustrated in the drawings is a preferred one because it will contain and dispense this blade which is in popular use. I will here premise that some of my objects are attained by reference to structural elements present in this blade and that others are attained without such reference. Blade openings B² and B³ are examples of the former and even these attain my objects whether formed independently or as enlargements of an already existing slot.

The magazine is comprised of the container 10 open at the top, closure 30 for this open top and spring 50 for elevating the blade stack to engage the topmost blade with the undersurface of the top closure 30. As will be pointed out herein-after, top closure 30 serves additionally to advance the topmost blade part way out of the container.

The blade receiving compartment of the container is defined by bottom 11, front and rear walls 12 and 13, and opposed side-walls 14. Lugs 15 project inwardly from the front and rear walls respectively. These lugs are dimensioned and located to engage in the cut away corners B⁴ which characterize the standard blade illustrated in the drawings to hold the blades stacked vertically with their shaving edges out of contact with the container walls.

The side walls 14 of the container 10 are reduced in thickness along their length to provide depressions or channels 16 lengthwise of the upper portion of their outer faces. The dimensions and contours of the cover approximate those of the outer faces of the upstanding walls of the container. The cover 30 is provided with flanges 31 depending downwardly from the opposed side edges thereof so that the cover can be assembled with the container by engaging the flange portions 31 of the former in the depressions or channels 16 of the latter. These flanges are so dimensioned that when in the assembled relation

of the parts, the outside faces of these flanges will be coplanar with the outer faces of the side wall portions therebelow. The assembly operation is facilitated by the fact that the flanges are sufficiently flexible to permit them to spread apart slightly for the assembly and then to relax into their intended position of engagement.

The front wall 12 of the container is reduced in height to leave shoulders 18 where it joins the side walls. This reduction in height of the front wall 12 is intended to approximate the thickness of the blade being dispensed. This thickness will be assumed for illustrative purposes to be of the order of .006". This reduction in the height of the front wall provides a passageway through which the topmost blade can be moved out of the container and is defined at the bottom by the top 17 of the front wall and at its sides by the shoulders 18. This passageway is closed at its top by the front end of the cover which is immediately thereabove.

Reference has been made to the fact that the cover 30 serves also to advance the topmost blade and the arrangement for doing this will now be set forth. The cover flanges 31 have spaced apart inwardly directed projections or teats 33 formed in any preferred or desired manner and so located and dimensioned that when these flanges 31 are engaged into the depression or channel 16 of the container, the projections or teats 33 will snap into the elongated aligned grooves or channels 25 provided in the channels 16 in the side walls of the container, so that the cover will be held thereby against accidental separation from the container. The grooves 25 in the container side walls are extended lengthwise of the containers to permit an advance of the cover relatively to the container. This advance is however limited by the length of these grooves 25. A comparison of Figs. 4 and 13 will show the extent of advance which the cover may be given.

Upon reference to Fig. 3 it will be observed that that portion of the rear wall 13 between the locating lugs 16 has been reduced in height to provide a depression which is defined by the lowered top portion 19 of the rear wall and the end shoulders 26.

The rear end of the cover is depressed centrally thereof as shown at 35 to provide the shoulder 36. The depressed area is dimensioned to fit into the aforementioned depression in the rear wall. It will be observed on viewing Fig. 8 that this shoulder 36 is located to the rear of the blade stack and it will be here stated that its height approximates the thickness of the blade. As a result the shoulder 36 will be in registration with the topmost blade so that if the cover is advanced from its position of Fig. 4, to its position of Fig. 13, the shoulder 36 will engage only the topmost blade and advance it and will clear the blade immediately therebelow.

By comparing Figs. 3, 4, 6 and 7, it will be seen that the front wall has a protuberance 23 (shown on enlarged scale in Fig. 6) projecting upwardly centrally from its top surface 17. Upon comparing Figs. 6 and 7, it will be seen that this protuberance comprises a portion 20 whose top face inclines downwardly rearwardly from the upper level at line 22 which is above that of top 17 of the front wall, to a lower level which is shown as slightly therebelow. For a blade thickness of the order of .006", it is found that a top level for the inclined face 21 of approximately .008" above the front wall top 17

and a bottom level of .002" below this top wall will adequately serve my purposes.

It will be further observed that the protuberance has a front portion 21 whose top face is shown as at the top level of the portion 20 and substantially parallel to the top 17 of the front wall. It will be observed further from Fig. 6 that the perimetrical or side walls of the portion 20 converge rearwardly toward the bottom level of that portion and that the perimetrical or side walls of the portion 21 converge forwardly. It will also be observed from Fig. 13 that the contours and dimensions of the protuberance are such when measured on a plane parallel to that of the top 17 of front wall 12, that the protuberance is free to enter that enlarged opened B² or B³ which is vertically thereabove and when so entered will bring these perimetrical or side portions into adjacency to the widest part of the opening B² or B³ so that retreat of the blade is prevented.

It will be observed that this inclined face portion 20 is presented in the path of the topmost blade in its advancement through the passageway and that during such advancement the lead edge of the blade will engage this inclined face portion or ramp and be flexed upwardly thereby as shown in Fig. 9 of the drawings.

The aforementioned protuberance 23 will obviously narrow the blade passageway therethrough. I will now describe the provisions whereby the blade can be cleared through this passageway notwithstanding this narrowing and whereby other objectives are attained.

Upon reference to Figs. 1, 4 and 8 it will be observed that the cover 30 is provided adjacent its front and rear edges with the arcuately shaped slots 37 and 37' which extend transversely of the long axis thereof. These arcuately shaped slots are shown as curved respectively into substantial parallelism with the adjacent front or rear edges of the cover member and are therefore presented with their concave curvatures in opposition. The cover portion intermediate these slots is corrugated transversely, as shown at 38 and upon reference to Fig. 8 it will be observed that these corrugations are directed entirely upwardly with reference to the lower or inner face of the cover and therefore present no portions which project below that inner face. It will be further observed upon viewing Fig. 8 that the cover portion 39 to the front of the slot 37, and the cover portion 40 to the rear of the slot 37' are shown as much thinner than the corrugated portion therebetween. As a result, the intermediate corrugated portion is relatively rigid because of its increased thickness and its corrugations; the front and rear cover portions 39 and 40 are inherently flexible because of their thinness; and the slots 37 and 37' isolate the front and rear cover portions 39 and 40 from the relatively rigid intermediate corrugated cover portion so that the former can flex freely without interference by the intermediate portion.

Upon reference to Fig. 12, it will be observed that the length of the corrugations 38 is such that the extreme beveled ends of the blades underlie the under surface of the cover 30 laterally of these corrugations and by reference to Fig. 1 it will be observed that the slots 36 and 37 extend slightly laterally beyond the ends of the corrugations. The results attained by this will be pointed out later.

Reference will now be made to the spring 50 shown in Fig. 2 of the drawings. This spring

comprises an upwardly concaved curve intermediate section 51, and downwardly concaved lateral end sections 53 and 54. The free ends 55 and 56 of section 51 are bent approximately to the horizontal as is also true of the free ends 57 and 58 of the lateral sections 53 and 54. This character of construction will have a levelling effect in seating the spring on the container bottom and in elevating the stack.

The assembly and loading of the magazine is effected as follows: the spring of Fig. 2 is seated on the container bottom and blades then stacked thereon and depressed to flatten the spring and to engage the cut away corners of the stacked blades with lugs 15. The cover flanges 31 are then entered into the channels 16 in the container side wall so that the protuberances 33 thereof engage in grooves 25. This completes the assembly operation to arrive at the loaded magazine shown in Fig. 4.

When it is desired to dispense a blade for use in a razor, the corrugated cover portion is engaged by a finger and advanced to its position of Fig. 13. In this movement, the shoulder 36 will engage the rear end of the topmost blade and advance it with the cover to engage its lead end B⁵ with the ramp 20 and move it therealong. In this movement, the lead end is flexed upwardly as shown in Fig. 9. The flexed lead end of the blade in turn engages and flexes upwardly the front portion 39 of the cover to thus increase the clearance through the passageway and apply a yieldable resistance to prevent undesired movement of the blade.

When the cover member has been advanced as shown in Fig. 13, protuberance 23 will underlie opening B³. The fixed end of the blade will then be free to relax to its normal plane to engage the opening B³ about protuberance 23. The cover 30 is then returned to its starting position to Fig. 4 to clear the projected lead end of the overlying cover as shown in Fig. 11 for manual engagement for moving the blade entirely out of the magazine. In this further manually effected movement to completely separate the blade from the magazine, the blade portions to the rear of the opening B³ will flex upwardly over the ramp 23 and correspondingly flex the front cover portion 39 so that the blade will at all times during its removal have a slight frictional resistance applied thereto by the flexed front cover portion 39 sufficient to prevent undesired or accidental movement thereof.

It will thus be seen that the arrangement herein disclosed permits the separation or projection from the stack of only the topmost blade and that at all stages in this separation, a yieldable resistance will be offered to blade movement. This arrangement also attains the further objective of preventing the retreat of the blade with the return of the cover. This is effected by the engagement of the front or lead portions of the opening B³ with the upstanding walls of protuberance portion 21.

I have described the details of construction of a specific embodiment as the preferred one for the reason, among others, that it services a well known and widely used specific type of blade. It will be understood however that the attainment of features of my invention permits of the wide

range of variation in the magazine construction to service the illustrated blade or other type blades for which the magazine may be devised. The specific magazine and blade structure shown in the drawings are therefore merely illustrative and elements thereof are significant in the attainment of my inventive features only when and to the detail with which their presence is set forth in the claims.

10 I claim:

1. A magazine for dispensing razor blades having a blade locating opening, said magazine being comprised of bottom, front, rear and side wall portions to define a compartment, a top closure for said compartment, means within the compartment for locating and maintaining a stack of blades therein in vertical registration with their shaving edges parallel to and spaced from said side wall portions and yieldable means beneath the stack for elevating it to engage the topmost blade of the stack with the inner face of the top closure, said front wall portion having a blade discharging passageway aligned with the topmost blade of the elevated stack, and of a height substantially equal to the blade thickness, and a projection extending upwardly from the bottom of and into said passageway, said projection being so dimensioned that it can enter the aforementioned locating opening in the blade, said top closure engaging the rear end of the topmost blade and being mounted for limited advancement for advancing the topmost blade through the passageway for a sufficient distance to bring its locating opening into vertical registration with said projection to permit the projection to enter the blade opening and thus prevent a reverse movement of the advanced blade.
2. A magazine as set forth in claim 1, wherein the projection presents an inclined surface to the advancing blade to flex its lead end upwardly until the lead end of the blade opening has cleared the projection to permit the blade to relax to bring the projection into abutting relation thereto to prevent retreat of the blade.
3. A magazine as set forth in claim 2 wherein the lead end of the top closure is yieldable to clear the flexed end of the blade through the passageway.
4. A magazine as set forth in claim 2 wherein the top closure is slotted transversely adjacent its lead end to render said lead end yieldable to clear the flexed lead end of the blade through the passageway.

EDGAR A. NELSON.
